(57) **CLAIM**

The ornamental design for a digital thermometer storage case, as shown and described.

DESCRIPTION

FIG. 1 is a top view of a first embodiment of a digital thermometer storage case showing our new design;

FIG. 2 is a bottom view thereof;

FIG. 3 is a front view thereof;

FIG. 4 is a rear view thereof;

FIG. 5 is a right side view thereof;

FIG. 6 is a left side view thereof;

FIG. 7 is a perspective view thereof showing the top and the right side of the digital thermometer storage case;

FIG. 8 is a top view of a second embodiment of a digital thermometer storage case showing our new design;

FIG. 9 is a bottom view thereof;

FIG. 10 is a front view thereof;

FIG. 11 is a rear view thereof;

FIG. 12 is a right side view thereof;

FIG. 13 is a left side view thereof; and,

FIG. 14 is a perspective view thereof showing the top and the right side of the digital thermometer storage case.

The broken lines shown in FIGS. 8, 10 and 14 are included for the purpose of illustrating portions of the digital thermometer storage case and form no part of the claimed design.
